CIRCUIT RESTORER

Robert F. Quinn, Schenectady, N. Y., assignor to
 General Electric Company, a corporation of
 New York

Application April 6, 1948, Serial No. 19,340

10 Claims. (Cl. 200—89)

1

My invention relates to circuit interrupters and more particularly to operating mechanisms for circuit breakers of the automatically operable reclosing type. More specifically, my invention is an improvement on the operating mechanism disclosed in application Serial No. 19,364, filed April 6, 1948, McCurry et al., which is assigned to the assignee to whom this application is assigned. In this McCurry et al. application, a recloser is claimed wherein a main motivating means opens the contacts in response to operation of actuating means which in turn is responsive to predetermined conditions of the controlled circuit, and wherein a time delay mechanism causes delay of closing operations and of predetermined opening operations of the recloser during persistent faults. My invention, furthermore, is related to application Serial No. 19,258, filed April 6, 1948, now Patent No. 2,619-562, dated November 25, 1952, Oppel et al. and to application Serial No. 19,213, filed April 6, 1948, now Patent No. 2,597,024, May 20, 1952, Oppel, which are both assigned to the assignee to whom this application is assigned. In these two applications, a recloser is claimed wherein collapsible means are utilized to interrelate the opening operations of the recloser contacts with a timing mechanism so as to modify the time current characteristic of the recloser upon the occurrence of predetermined conditions of the controlled circuit.

In operating mechanisms for reclosing circuit breakers of the type disclosed in the above-mentioned application of McCurry et al. in which provision is made for both instantaneous and time-delayed opening operations, it is possible that the time-delayed opening operations, though fully capable of proper functioning for moderately excessive fault currents, may be too prolonged where the magnitude of the fault current is of the order from, say, 20 to 30 times the normal full-load rating of the device.

A principal object of my invention is the provision of an operating mechanism for electric circuit reclosers having improved time current characteristics.

Another object of my invention is to provide an operating mechanism for reclosing circuit breakers which is capable of increasing the interrupting rating of the device without increasing the physical size or normal current carrying capacity thereof.

A further object of my invention is to provide a reclosing circuit breaker such as that disclosed in the above application of McCurry et al. which has greatly improved time current characteristics

2

without interfering with the normal sequence of operations for persistent fault conditions which eventually result in a final lock-out or locked-closed operation.

- 5 Still another object of my invention is the provision of a much faster time-delayed opening where the fault current is of an exceptionally high magnitude while maintaining the same operating characteristics for relatively low fault currents.
- 10 Still another object of my invention is to retain the advantages to be derived from the use of a recloser operating mechanism of the type disclosed in the above-mentioned application of McCurry et al. and at the same time to provide such a mechanism with means for substantially decreasing the time delay occurring for certain preselected opening operations if the fault current happens to be in excess of a predetermined 15 relatively high value of the order of 20 or more times the normal rated current carrying capacity of the device.

20 Further objects and advantages of my invention will become apparent as the following description proceeds and the features of novelty which characterize my invention will be pointed out with particularity in the claims annexed to and forming a part of this specification.

25 For a better understanding of my invention, reference may be had to the accompanying drawings in which Fig. 1 is a family of curves showing the time-delayed opening time current characteristics of a reclosing circuit breaker embodying my invention as well as the time current characteristic curves of fuses which are coordinated with the recloser; Fig. 2 is an elevational view in section of a recloser embodying my invention; Fig. 3 is a schematic representation of the circuit incorporated in the recloser shown in Fig. 2 and in which Fig. 4 is an elevational view in 30 section of a small portion of Fig. 2.

35 In electric distribution systems it is desirable to obtain the maximum protection possible per dollar of investment in protective equipment. Frequently it proves feasible in a particular distribution system to combine automatically operable reclosing devices and fuses. Fuses may be inserted into the line between the source of power and the recloser and may also be placed in the line between the recloser and the load.

40 45 50 55 With reference to Fig. 1, the dotted line curve *pq* represents a desirable time current curve for the recloser while the curve *ab* represents the time current characteristic of a reclosing device such as that disclosed in the above-mentioned application of McCurry et al. The curves *c*, *d*,

and *e* represent the time current characteristics of fuses inserted in the line between the source of power and the particular reclosing device. The longer time characteristics of the fuses will delay the operation thereof until the recloser will have had an opportunity to open the circuit. The curves *f*, *g* and *h* represent the time current characteristics of fuses inserted into the system at points between the load centers and the particular recloser. The shorter time characteristic of this latter group of fuses will permit a particular fuse to blow and thereby disconnect the faulted load center from the system without causing the recloser to operate.

It is apparent from Fig. 1 that the fuse characteristic curves *c*, *d* and *e* intersect the recloser time-delayed characteristic curve *aib* between points *i* and *b*. Conversely stated, a recloser having a time current characteristic such as *aib* would be too slow in opening with time delay where the fault current were excessively high say of the order of magnitude of 30 times the normal current rating of the recloser, for instance. It is apparent that, in order to overcome this difficulty, the recloser time-delayed characteristic curve *aib* should be modified somewhat to decrease the time required for time-delayed opening operation for very high currents without necessarily changing the time required for time-delayed opening for lower fault currents.

In accordance with my invention, I provide means for modifying the curve *aib* by causing such curve to assume the shape *aij* and thereby I more nearly approximate the desirable curve *Pq* and also avoid the possibility of a failure of coordination between fuses having characteristics such as *c*, *d*, and *e* and the recloser when opening with time delay.

Referring now to Figs. 2 and 3, the circuit shown in Fig. 3 comprises a pair of main or interrupting contacts 1 and 2, a bridging member 3, and a main operating coil 4 for opening the circuit through the main contacts 1 and 2 by moving the bridging member 3 out of engagement with the main contacts. A relay coil 5 controls the opening of normally closed relay contacts 6 and 7. One end 8 and the other end 9 of the circuit shown in Fig. 3 are connected to the two terminals of the recloser, only one of which is shown in the drawings and which is designated by the numeral 10. It will be seen that main operating coil 4 is short circuited by relay contacts 6 and 7 during normal service conditions and that relay coil 5 carries line current when main or interrupting contacts 1 and 2 are engaged by bridging member 3. Thus excessive current will activate relay coil 5 which will open its contacts 6 and 7 thereby diverting full current through the main operating coil 4 which will then cause the bridging member 3 to move out of engagement with contacts 1 and 2 to complete an interrupting operation. Terminal 10 and the other terminal of the device, not shown, are both mounted within insulators such as 11 which are mounted into the cover plate 12 of the device by means of adapter elements 13 and 14 and by the bolts 15. The operating mechanism is completely enclosed within a metallic tank 16 which has an insulating lining 17 covering its inner surface. The tank 16 contains an insulating fluid such as oil. The cover 12 may be secured to the tank 16 by any suitable means such as by a plurality of bolts which are not shown. Formed into the flange 18 of the tank 16 is a peripheral groove 19. A gasket 20 is disposed within the groove 19.

19 and bears against the flange 21 of the cover 12 to seal the tank and thereby to prevent the leakage of oil from within the tank 16 between the engaging surfaces of the flanges 18 and 21.

5 The circuit breaker may be supported on a distribution circuit pole or the like by means of suitable studs or bands, not shown, which are welded or otherwise secured to the outer surface of the tank 16. It is evident from Fig. 2 that 10 the operating mechanism embodying my invention depends from and is supported by the cover 12. Thus it will be seen that the whole mechanism may be removed from the tank 16 by unbolting and lifting the cover upwardly.

15 For the purpose of supporting the mechanism, a substantially U-shaped supporting structure 25 is used whose base or bight portion 26 is secured by welding or otherwise to cover plate 12. Since Fig. 2 is a sectional view, the base portion 26 appears in section and the forward prong or side plate of the U does not appear. The lower edge of each side plate of the supporting structure 25 is flanged as at 36 and to which flange is bolted the supporting posts 27. Secured to the lower 25 ends of the posts 27 is the assembly generally indicated at 28. The assembly 28 includes a horizontal metallic supporting plate 29 to which the supporting posts 27 are secured by any suitable means such as the nuts 30. Secured to the supporting plate 29 by means of bolts such as 32 30 are a plurality of L-shaped members or angle lugs 31. Secured to the L-shaped members 31 are the laminated magnetic structures 33 and 34 which support the main operating coil winding 4 35 and the relay coil winding 5 respectively. Secured to the lower end of the laminations 33 and 34 are the angle members 37 having horizontal flanges 38. Secured to the angle members 37 there is shown another horizontal metallic supporting plate 39 which is bolted as at 40 to the flanges 38 of the angle members 37. The interrupting chamber generally indicated at 41 comprises a lower horizontal plate 42 constructed of insulating material and side walls 43 which 45 also are constructed of insulating material. The plate 42 depends from the plate 39 through the agency of bolts 44 which are screwed into insulating pillars 45 of which only one is shown. The main interrupting contacts 1 and 2 are disposed within the arcing chamber 41 and are supported on the bottom plate 42 thereof by means of terminal bolts 46 and 47. The bridging member 3 is secured to armature 48 by any semi-rigid construction which is adequate to achieve 50 a wiping engagement and disengagement between the bridging member 3 and contacts 1 and 2. Suitably arranged oil expulsion ports 112 are provided to allow pressure due to arcing to escape from the arcing chamber 41. For the purpose of biasing the bridging member 3 and parts 55 associated therewith toward the closed position, the compressional spring 49 is used.

The relay contacts 6 and 7 are operated by the mechanism generally indicated by the numeral 59 in such a way as to delay the opening of the contacts 6 and 7 until the armature 51 of the relay has been moved upwardly to a point near the end of its opening stroke for purposes which will become apparent as the description proceeds.

60 The mechanism 59 incorporates the link 52 which is pivotally connected as at 53 to the relay armature 51. The lower end of link 52 is pivoted at 54 to the member 55 which in turn 65 is pivoted to a fixed fulcrum 56 secured to the

arcng chamber wall 43 or which may be supported in any other suitable manner. It will be observed that the member 55 is constructed with the projection 57 extending along a portion of its upper edge and also that the member 55 is provided with an apertured projection 58 which serves as a means for mounting one end of the tension spring 59. Also pivotally mounted at 56 is a member 60 is an apertured projection 61 to which is attached the other end of the spring 59. Member 60 is also provided with a projection 62 which engages one end of the compression spring 63. The member 60 is also provided with a projecting pin 64 which engages a holding recess of the curved hook-type latch member 65 which is mounted upon a fixed pivot 66 which pivot may be secured to the wall 43 of the arcng chamber. A torsion spring 70 serves to bias the member 65 for rotation in the counterclockwise direction against the pin 64 mounted on the member 60. It will be observed that the edge surface 67 of the member 60 abuttingly engages the projection 57 on the member 55. The contact arm 7 is pivotally mounted at 56 and is provided with a recess 68 into which the projection 62 on the member 60 is movable. The bottom of the recess 68 constitutes a small platform upon which the small compression spring 63 is supported. The contact arm 7 is also constructed with a recess 69 which cooperates with the projection 61 on the member 60 by affording only limited angular movement between these two members.

The operation of the latch-closed switch 50 is as follows: Whenever the relay coil 5 is sufficiently energized to impart upward movement to its armature 51, the link 52 is elevated carrying with it the right hand end of the member 55. This motion of member 55 removes its projection 57 away from the surface 67 of the member 60, and, as the member 55 is rotated counterclockwise about the pivot 56, the spring 59 is elongated somewhat and an increased counterclockwise movement is thereby exerted on the member 60. Member 60 is prevented from rotating in the counterclockwise direction, however, for a short time due to the engagement of its overhung pin 64 with the latching recess of the curved latch member 65. As the arm 52 continues rotating upwardly, the forwardly projecting pin 54 eventually engages the curved latch member 65 and causes such member to be rotated in the clockwise direction about its fixed pivot 66 to unlatch the pin 64. Accordingly the increased pull of tension spring 59 will now cause rapid counterclockwise rotation of the member 60 about fixed pivot 56. This counterclockwise rotation of member 60 will cause the contact arm 7 to be rotated counterclockwise due to the engagement of the projection 61 on the member 60 with the upper edge of the recess 69 in the contact arm 7. In this way the contacts 6 and 7 are separated thereby removing the short circuit from around the main operating coil 4 which diversion causes the whole fault current to flow through coil 4 and thereby initiates an opening operation of the bridging member 3.

When relay armature 51 is allowed to descend as will be more fully explained hereinafter, the link 52 moves downwardly thereby causing the member 55 to be rotated clockwise. Because the projection 57 on the member 55 again is in engagement with the surface 67 of the member 60, members 57 and 60 rotate clockwise in unison to their reset position. The projection 61 within recess 69 on the member 60 causes the contact 75

arm 7 also to move clockwise with members 57 and 60 about the pivot 56 and eventually causes the contact 7 to re-engage the contact 6. In the meantime the pin 64 on the member 60 will have moved along the curved surface of the member 65 back to its original latched position as shown in Fig. 2. The contact pressure spring 63 will help cushion the reclosing switch parts after the contacts 6 and 7 make contact.

It is apparent that the latch-closed switch 50 will maintain the contacts 6 and 7 in engagement during the initial portion of a circuit opening operation and will permit the contacts to separate only after the relay armature 51 has moved to a point very near to the end of its stroke.

The timing mechanism embodied in my invention is generally designated by the numeral 72 which mechanism will now be described. The numeral 73 designates a fixed shaft which is supported at the front and rear by depending side portions 74 which are formed integrally with the downwardly extending side plates of the generally U-shaped supporting structure 25.

As pointed out above, only the rear one of these downwardly projecting arms is shown and is in broken lines in the drawings. Rotatable about the shaft 73 is a ratchet wheel 75 which has notched or toothed portions 76 and 77 about its periphery and which also is provided with the smooth or unnotched intermediate peripheral portions 78 and 79. Also rotatable about the shaft 73 is a gear wheel 80 whose entire periphery is provided with gear teeth. Ratchet wheel 75 and gear wheel 80 are connected together by a spring mechanism, which will be described hereinafter, so that under certain conditions they rotate in unison. Both the ratchet wheel 75 and the gear wheel 80 are provided with an arcuate slot 81 for a purpose which will be apparent as the description proceeds. Secured to the gear wheel 80 and rotatable about shaft 73 as a center point is a pulley 82, which is shown only in Fig. 4, on the periphery of which is wound a flexible cord 83, one end of which is affixed to some point on the periphery of the pulley 82 and the other end of which is tied to the tension spring 84. The opposite end of spring 84 is attached to aperture 85 in a downturned portion of the supporting plate 26. The tension spring 84, as will be evident from the drawings, is adapted to exert a counterclockwise turning moment on the gear wheel 80 and is for the purpose of resetting the ratchet and gear wheels as will be more fully understood as the description proceeds.

The speed of rotation of ratchet wheel 75 and of gear wheel 80 is governed by an escapement mechanism which will now be described. Secured to the downwardly extending sides of the supporting structure 25 having the base 26 is a shaft 90. Rotatable on shaft 90 is a pinion 91, the teeth of which engage the teeth of the gear 80 at all times. Secured to the pinion 91 and rotatable therewith is a ratchet wheel 92 which cooperates with the oscillatory escapement verge member 93 which is pivoted at its center point to the pin 94 which pin is secured to the supporting arms 25. Rotation of gear 80 will cause rotation of pinion 91, ratchet wheel 92 and the interaction between the teeth of the ratchet wheel 92 and the projections of the oscillatory verge member 93 will afford a watch-type escapement device having a time-delaying action in a manner well known in the art.

In order to interrelate the opening operations of the relay armature 51 and the ratchet wheel 75, an opening pawl 96 is pivot-

ally mounted at 97 across the spaced arms of a U-shaped carrier member 98, which member is pivoted at 73. A torsional spring 99 is used to bias pawl 96 for rotation about pivot 97 in the clockwise direction so that, unless prevented from doing so, the pawl 96 will engage the periphery of the ratchet wheel 75. The carrier 98 is connected to the connecting link 100 by a pin 101 which is interposed between and secured to the front and rear arms of the U-shaped member 98 and which pin is adapted to ride in the arcuate slots 81 in both the ratchet wheel and the gear wheel. The lower end of the link 100 is pivotally connected to the armature 51 by any suitable means such as by the pin 35.

In order to cause the pawl 96 to become disengaged from the periphery of the ratchet wheel 75 when the carrier member 98 is in the position shown in Fig. 2, a projection 102 is provided which is secured by any suitable means to a downwardly extending portion of one or both the sides of the U-shaped supporting structure 25.

For the purpose of interrelating the closing operations of the armature 48 and the ratchet wheel 75 and the gear wheel 88, a closing pawl 105 is provided. Pawl 105 is pivotally mounted to arm 106 by any suitable means such as by a pin 107. The pawl 105 is biased for rotation about pivot pin 107 in the clockwise direction by means of a torsional spring 108. Arm 106 is pivotally supported at its left hand end on the shaft 73. In order to cause the pawl to disengage the periphery of the ratchet wheel 75 as is required during a circuit closing operation, a pin 109 is provided which is supported by a downwardly extending portion of one or both the sides of the supporting structure 25. A link 110 is connected at its upper end to the arm 106 by the pin 107 and at its lower end a pivotal connection 111 serves to connect the link 110 to the armature 48 which is disposed within the main opening coil 4.

For the purpose of automatically locking the interrupter contacts in the open position after the circuit breaker has performed a predetermined number of opening and closing operations, a linkage mechanism is provided which will now be described. An arm 113 is rotatable about the fixed shaft 90 and is apertured at its upper end for connection to the tension spring 114 which biases the arm 113 for rotation in the clockwise direction. The arm 115 is pivotally connected at its left hand end to the lower end of the arm 113 by a pin 116. Arm 117 is pivotally connected to the right hand end of the arms 115 and 106 by a pivotal connection to the opening pawl pivot pin 107. Arm 117 is provided with a slot 118 through which the pin 119 is slidable. Pin 119 is mounted on an arm 120 which is pivoted at 121 to the supporting structure 25. A tension spring 122 is connected at its left hand end to the supporting structure 25 and at its right hand end to the pin 119. A pin 123 is secured to the ratchet wheel 75 and hence is rotatable therewith, the ratchet wheel functioning as a counting device to determine the number of operations of the recloser during a persistent fault. When the mechanism is operated so as eventually to advance the pin 123 from the normally closed position of the recloser as a result of several successive reclosures, the arm 113 will be rotated slightly by the pin 123 in the counterclockwise direction about its supporting shaft 90 against the action of the tension spring 114. This action causes the link 115 to be moved to the right, a suitable slot being

provided in this link to permit this movement. Immediately following this motion to the right of link 115, link 110 will be moved upwardly due to the final opening operation which will move the slotted link 117 upwardly. Movement to the right of link 115 together with upward motion of link 118 causes the right-hand end of link 115 to collide with pin 119. This collision will rotate the arm 120 in the counterclockwise direction about fixed pivot 121. This movement of arm 120 will move the spring 122 over center. The spring 122 will cause substantial counterclockwise rotation of the arm 120 about its pivot 121 so that finally the pin 119 becomes effective to hold up the whole main switch movable structure in open-contact position by engaging the upper end of the slot 118 in 117. Prior to the collision of pin 123 and arm 113, the link 115 is rotated during opening and closing operations about pin 116 with this pin in the position shown in Fig. 2. With pin 116 so located, link 115 clears the pin 119 and the mechanism is not locked open.

For the purpose of closing the main contacts after the breaker is locked-out and for the purpose of manually opening the main contacts, a bell-crank having an external arm 125 is provided which is pivoted to a fixed fulcrum 126. Opening 127 is incorporated in the right hand end of the arm 125 and an opening 128 is incorporated in the left hand or internal arm of the bell-crank. If the breaker is closed and if it is desired to manually open the breaker, a switch hook is manually inserted into the opening 127 and then pulled downwardly, thereby turning the bell-crank through a clockwise movement. Accordingly, when the lower edge of the opening 128 engages pin 119, the link 117, the link 110, the armature 48, and the bridging member 3 are all elevated and hang from the pin 119 in the contact open position so that the device will remain locked-open by the open toggle position of spring 122 and toggle link 120 as described for the automatic lock-out procedure.

If the device is locked-open manually or automatically, in order thereafter to close the contacts, it is only necessary to elevate the right hand end of the arm 125 thereby rotating the bell-crank in a counterclockwise direction about its pivot 126 which action restores spring 122 and toggle link 120 to their stable normal overcenter position and permits the arm 117, the arm 110, the armature 48 and the bridging member 3 to be lowered to close the contacts under the action of biasing spring 49. In order to cover the opening in the cover 12 through which the arm 125 extends, a cowl 129 is provided.

It will be understood that the device could be adapted to perform, within limits, a relatively wide range of opening and closing operations wherein certain of these operations would be time-delayed and wherein certain others could be made to occur almost instantly. For persistent faults the particular device described above and shown in Fig. 2 is adapted to perform a first instantaneous opening operation followed by a time-delayed closing operation, a second instantaneous opening operation followed by a time-delayed closing operation, a third opening operation which is time-delayed followed by a third time-delayed closing operation, and a fourth opening operation which is time-delayed followed by a final lock-out operation.

Assuming that the interrupter is closed as shown in Fig. 2, a fault condition on the circuit

controlled by the device will cause an excess amount of current to flow through the relay coil 5 which will immediately cause its armature 51 to move upwardly. As the armature 51 moves clockwise about the shaft 73 and the opening upwardly, the U-shaped carrier 98 will move pawl 96 will become disengaged from the projecting member 102. Torsional spring 99 thereupon will rotate pawl 96 in the clockwise direction causing the pawl to engage the smooth portion 78 of the ratchet wheel 75. Hence, pawl 96 will be free to slide along the ratchet wheel 75 without appreciable impediment, so that the armature 51 and parts associated therewith will move substantially instantaneously in the upward direction. Near the end of the upper limit of travel of the armature 51, the contacts 6 and 7 will open as previously explained, the short circuit around main operating coil 4 will thereby be removed and the main coil 4 will be forced to carry the full amount of the fault current. This current will cause the armature 48 to move rapidly upward against the bias of spring 49. Upward movement of armature 48 will elevate the link 110 and in turn cause the closing pawl 105 to move upwardly in a counterclockwise direction with respect to the ratchet wheel 75. Bridging member 3 will move out of engagement with contacts 1 and 2 and the circuit will be interrupted, thereby deenergizing coils 4 and 5 and terminating the upward force on their armatures. When this opening movement has progressed a slight distance, the pawl 105 will become disengaged from the stop 108 and the torsional spring 108 will rotate the pawl 105 in a clockwise direction about the pivot 107. This clockwise rotation of pawl 105 will cause the pawl to engage the smooth portion 79 of the ratchet wheel 75 for a limited time. When the armature 48 has reached the limit of its upward travel, the pawl 105 will engage the toothed section 77 of the ratchet wheel 75. The bias of spring 49 together with the weight of the parts will automatically cause the armature 48, the bridging member 3, the connecting link 110, pawl 105 and armature 115 to move downwardly. Because the pawl 105 now is in engagement with the toothed section 77 of the ratchet wheel 75, downward motion of pawl 105 will cause clockwise rotation of the ratchet wheel 75 and the gear wheel 80 to which it is coupled. Rotation of gear wheel 80 will rotate the timer ratchet wheel 92 through the pinion 91 and time-delay will be achieved by the oscillatory motion of the verge or escapement member 93 about the perimeter of the ratchet wheel 92. Thus, the closing operation of the device will be time-delayed so that the interrupting contacts are maintained open for a predetermined short period of time. If the fault condition should have cleared itself, the bridging member 3 will remain in engagement with the contacts 1 and 2 and the ratchet wheel 75 and the gear wheel 80 will be rotated in a counterclockwise direction to the reset position as shown in Fig. 2 by the action of spring 84 and flexible cord 83 which reels off the pulley 82.

Should the fault persist, however, another opening operation will be initiated. The smooth portion 78 of the ratchet wheel 75 is sufficiently long to afford no opposition to upward opening movement of the opening pawl 96 during the second opening operation. The device, therefore, will open substantially instantaneously as previously described and will reclose with time-delay as already described since the closing pawl 105

will still be operating on the notched section 77 of the ratchet wheel.

Should the fault condition persist after the second reclosing operation, the relay coil 5 then will elevate its armature 51 but at a slower rate than before because the preceding two time-delayed reclosing operations will have been sufficient to advance the ratchet wheel 75 in a clockwise direction to a point where the notched portion 76 of the ratchet wheel 75 will be presented for engagement with the opening pawl 96. Accordingly, upward motion of armature 51, connecting link 100, arm 98 and pawl 96 will cause the ratchet wheel 75 and the gear wheel 80 to rotate in a clockwise direction. This clockwise rotation rotates the timer ratchet wheel 92 through the pinion 91 and, as previously explained for the reclosing operation, time-delay will be achieved through the oscillatory action of the escapement member 93 whereby the interrupting contacts now are maintained closed for a short period of time. When the armature 51 has reached a point near the end of its upward travel, the relay contacts 6 and 7 will be opened as previously described and main coil 4 will be effectively energized thereby elevating bridging member 3 to open the circuit. The two reclosing operations performed with time-delay and the one opening time-delayed operation thus far described will not have been sufficient to advance the notched section 77 of the ratchet wheel 75 beyond the closing pawl 105 and so the pawl 105 again will engage the notched section 77 of wheel 75 and cause the main contacts to close once more with time-delay as previously described.

Should the fault still persist, the interrupter will open with time-delay as described above in connection with the third opening operation since the opening pawl 96 will still be in a position to engage the advanced toothed section 76 of the ratchet wheel 75. Upon completion of this fourth and final opening operation, the pin 123 will have been advanced from its initial position shown in Fig. 2 to the region where it encounters arm 113 of the lock-out linkage whereby the toggle arm 120 is rotated up from over center with respect to spring 122 to achieve final lock-out as already described. Briefly restated, the engagement of the pin 123 with the arm 113 causes a slight counterclockwise rotation of the arm 113 about its fixed supporting pin 90 which operation, when followed by an interrupting contact opening operation which elevates the armature 48, the link 110, and the link 117 upwardly, will now produce interference between the outer end of laterally displaced tripping link 115 and the projecting pin 119 whereby to rotate the toggle link 120 toward its locked-out position. Obviously, the force of the hold-open spring 122 is sufficient to overcome the force of the contact closing spring 49.

It may be perceived that the device can be converted from a locked-open device as above described to a locked-closed device. For this purpose it is only necessary to dispose a fixed pin on any fixed structure, such as the supporting structure 26, in such a position that it will engage a pin disposed on the ratchet wheel 75 so that immediately after the device has performed the desired number of opening and closing operations, the pin on the ratchet wheel will engage the fixed stop so as to prevent upward motion of the armature 51 (and parts associated therewith) through the agency of the opening pawl

96, thereby preventing the opening of the contacts 6 and 7 so that consequently the interrupting contacts are maintained closed. In this way a fault condition on the circuit is forced to either burn itself off or to blow an appropriate fuse or, in the event of fuse failure, to trip a station breaker.

The recloser so far described is not my invention but rather is as disclosed in the aforementioned application Serial No. 19,364, filed April 6, 1948, McCurry et al.

In accordance with my invention, I have provided resilient or collapsible coupling means for permitting the ratchet wheel 75 to rotate somewhat independently of the gear wheel 80 when the opening pawl 96 is in engagement with the toothed section of the ratchet wheel 75, whenever the fault current is in excess of a predetermined relatively large value. As is more clearly shown in Fig. 4, I secure to the gear wheel 80 a stud 130 and I secure to the ratchet wheel 75 a stud 131. Mounted about the shaft 73 and secured at the end portions thereof to the studs 130 and 131 is a spiral spring 132, which spring is the only means interconnecting the gear 80 in driving relationship with the ratchet wheel 75.

With this arrangement it will be appreciated that while the gear 80 is still directly subject to the inertia or retarding effect of the timer escapement mechanism, the ratchet wheel now is subject to this timer control only through the intermediary of the spring 132. It will be clear that I may make the spring of any appropriate strength and that furthermore I can arrange suitable coacting stop members such as 133 on the ratchet and 134 on the gear for imparting a predetermined amount of preloading to the spring connection 132.

I choose the strength, gradient and preloading of the spring 132 so that, for overcurrents below a certain predetermined value, the spring functions substantially as a rigid connection whereby the ratchet wheel 75 is fully subject to the moderating influence of the timer mechanism as before. On the other hand, above this predetermined current value, the spring is collapsible so that the ratchet 75 can be rotated with respect to gear wheel 80 and to a degree commensurate with the overcurrent; consequently, for time-delayed opening operations, the period which the relay contacts are maintained closed (by virtue of the opening pawl 96 engaging the ratchet wheel) is lessened not only due to the higher opening force transmitted to the timer mechanism which increases the oscillation rate but also because of the decreased amount of actual rotation imparted to the gear wheel 80 due to the virtual "slippage" the spring 132 has permitted between ratchet and gear up to the instant that the relay contacts have parted.

In the embodiment shown, the spring is strong enough to be deflected only in accordance with time-delayed opening operations; i. e., reclosing forces applied to the ratchet through the closing pawl 105 are not great enough to produce overtaking movement of the ratchet wheel 75 with respect to its associated gear 80.

The counterclockwise moment exerted on the ratchet wheel 75 due to the precharged spring 132 is of such a value that a time-delayed opening operation of the pawl 96, the link 100, the armature 51 and the contact 7 will proceed with time-delay if the fault current on the line, and hence the force exerted by coil 5, is below a predetermined amount, in which case the gear wheel 75

80 and associated time-delaying mechanism will be operated. Otherwise stated, the curve *aij* of Fig. 1 will coincide with the curve *aij* of Fig. 1 in so far as the common portion *ai* of these two curves is concerned.

If, however, the fault current is in excess of a predetermined value of the order of 20 to 30 times normal line current, the upward force exerted by armature 51 through link 100 on pawl 96 will be sufficient to overcome very rapidly the counterclockwise moment exerted by the spring 132 on the ratchet wheel 75. The ratchet wheel, therefore, will be free to rotate in the clockwise direction without appreciable time-delay while the gear wheel 80 and the associated time-delaying mechanism will remain substantially stationary. Otherwise stated, the characteristic curve of the recloser will follow the line *ij* rather than the line *ib* and better coordination between the recloser and the fuses having the characteristics *c*, *d*, and *e* as shown in Fig. 1 will be achieved.

It will also be apparent that the incremental angular displacement of the ratchet wheel 75, due to the rotation of the wheel by the closing pawl 105 and by the opening pawl 96, will remain unaffected so that any predetermined sequence of opening and closing operations will proceed, as explained above, to a final lock-out or lock-closed condition of the device in just the same manner as formerly where the ratchet gear wheels were directly coupled together.

While I have shown and described a particular embodiment of my invention, it will be obvious to those skilled in the art that various changes and modifications may be made without departing from my invention in its broader aspects and I, therefore, intend in the appended claims to cover all such changes and modifications as fall within the true spirit and scope of my invention.

What I claim as new and desire to secure by Letters Patent of the United States is:

1. An electric circuit reclosing device for performing a cycle of opening and closing operations and thereafter for automatically assuming a locked open position comprising relatively movable contacts, condition responsive means for operating said contacts, means for locking said contacts in the open circuit position, counting means adapted for incremental movement, means operatively connecting said counting means and said condition responsive means, said counting means being movable in response to operation of said condition responsive means for causing operation of said means for locking said contacts in the open circuit position after a predetermined number of operations of said contacts, a timing mechanism, and yieldable biasing means normally biasing said counting means into engagement with said timing mechanism to cause said timing mechanism and said means adapted for incremental movement to move in unison to delay operation of said contacts during circuit closing operations and whenever the opening force developed by said means for operating said contacts is below a predetermined magnitude during preselected opening operations due to a fault condition, said yieldable biasing means being yieldable only in response to opening forces in excess of said predetermined magnitude so as to cause relative movement between said timing mechanism and said means adapted for incremental movement.

2. An operating mechanism for an electric circuit reclosing device having relatively movable contacts comprising, electromagnetic means responsive to fault currents for opening said contacts, means for imparting closing movement to said contacts, a timing mechanism, means including a rotatable member and a precharged collapsible member connected with said timing mechanism and disposed in cooperative relation to said electromagnetic means for interrelating opening and closing operations of said contacts with said timing mechanism, said rotatable member being provided with means for establishing an operative relationship between said rotatable member and said electromagnetic means, only during preselected closely succeeding opening operations of said device, said collapsible member being operable to cause said timing mechanism to operate in unison with said rotatable member to delay operation of said contacts during closing operations of said device, and also, during said preselected opening operations of said means for opening said contacts when the value of the fault current is below a predetermined amount, said collapsible member being collapsible only in response to fault currents in excess of said predetermined value to cause relative movement between said rotatable member and said timing mechanism.

3. An electric circuit reclosing device for performing a cycle of opening and closing operations and thereafter for automatically assuming a locked open position comprising relatively movable contacts, current responsive means for operating said contacts, means for locking said contacts in the open circuit position, means including a ratchet wheel rotatable in response to preselected operations of said means for operating said contacts for causing operation of said means for locking said contacts in the open circuit position after a predetermined number of operations of said contacts during a persistent fault condition, a timing mechanism, and yieldable biasing means interposed between said timing mechanism and said ratchet wheel and normally biasing said ratchet wheel into engagement with said timing mechanism, said biasing means being effective to cause said ratchet wheel and said timing mechanism to move in unison for opening forces developed by said means for operating said contacts which are below a predetermined magnitude, said biasing means being yieldable only in response to opening forces in excess of said predetermined magnitude to cause relative movement between said timing mechanism and said ratchet wheel.

4. An electric circuit reclosing device for performing a cycle of opening and closing operations and thereafter for automatically assuming a locked open position comprising relatively movable contacts, current responsive means for operating said contacts, means for locking said contacts in the open circuit position, means including a ratchet wheel rotatable in response to preselected operations of said means for operating said contacts for causing operation of said means for locking said contacts in the open circuit position after a predetermined number of operations of said contacts during a persistent fault condition, a projection on said ratchet wheel, a timing mechanism including a rotatable member, a projection on said rotatable member, and a precharged spring interposed between said ratchet wheel and said rotatable member and effective normally to bias the projection on said

5 ratchet wheel and on said rotatable member into engagement, the biasing force exerted by said spring being sufficient to maintain said projections in engagement and to cause said ratchet wheel and said rotatable member to rotate in unison when the opening force exerted by said means for operating said contacts is below a predetermined value, the biasing force exerted by said spring being insufficient to prevent relative movement between said ratchet wheel and said rotatable member when the opening force exerted by said means for operating said contacts is in excess of said predetermined value.

5. An operating mechanism for an electric circuit reclosing device having relatively movable contacts comprising, electromagnetic means responsive to fault currents for imparting opening movement to said contacts, means for imparting closing movement to said contacts, a timing mechanism, means including a rotatable member and a precharged collapsible member connected with said timing mechanism and disposed in cooperative relation to said electromagnetic means for interrelating opening and closing operations of said contacts with said timing mechanism, said rotatable member being provided with means for establishing an operative relationship between said rotatable member and said electromagnetic means, only during preselected closely succeeding opening operations of said device, said collapsible member being operable to cause said timing mechanism to operate in unison with said rotatable member to delay operation of said contacts during closing operations of said device and also during said preselected opening operations of said device when the value of the fault current is below a predetermined amount, said collapsible member being collapsible only in response to fault currents in excess of said predetermined value to cause relative movement between said rotatable member and said timing mechanism, and means operable in response to a predetermined angle of rotation of said rotatable member for locking said contacts in the open circuit position.

6. An operating mechanism for an electric circuit reclosing device having relatively movable contacts comprising, means responsive to fault currents for opening said contacts, means for imparting closing movement to said contacts, a timing mechanism, a rotatable member, means movable by said means responsible to fault currents for operating said rotatable member in response to an opening operation of said device, means movable by said means for imparting closing movement to said contacts for operating said rotatable member upon closing movement of said contacts, a resilient member connecting said rotatable member with said timing mechanism, said resilient member permitting opening movement of said means for opening said contacts without affecting said timing mechanism when the fault current is in excess of a predetermined amount, said resilient member upon lesser fault currents being effective operably to connect the rotatable member with the timing mechanism for retarding substantially the full opening movement of said means for opening said contacts.

7. An operating mechanism for an electric circuit reclosing device having relatively movable contacts comprising, means responsive to fault currents for opening said contacts, means for imparting closing movement to said contacts, a

timing mechanism, a rotatable member, means movable by said means responsive to fault currents for operating said rotatable member upon closely succeeding preselected opening operations of said device, means movable by said means for imparting closing movement to said contacts for operating said rotatable member upon closing movement of said contacts, a resilient member connecting said rotatable member with said timing mechanism, said resilient member permitting at least a partial opening movement of said means for opening said contacts without affecting said timing mechanism when the fault current is in excess of a predetermined amount, said resilient member upon lesser fault currents being effective operably to connect the rotatable member with the timing mechanism for retarding substantially the full opening movement of said means for opening said contacts.

8. An operating mechanism for an electric circuit reclosing device having relatively movable contacts comprising first means responsive to fault currents for opening said contacts, second means for imparting closing movement to said contacts, a movable member, means responsive to an opening operation of said first means for moving said movable member, a timing mechanism, precharged resilient means interposed between said timing mechanism and said movable member, said resilient means being yieldable to render said timing mechanism ineffective to retard at least a portion of the opening movement of said first means when the fault current is in excess of a predetermined value, said resilient means remaining substantially nonyielding so as to cause operation of said timing mechanism to delay the opening operation of said first means in response to smaller fault currents.

9. An operating mechanism for an electric circuit reclosing device having relatively movable contacts comprising electromagnetic means for imparting opening movement to said contacts, relay means responsive to fault currents for initiating operation of said electromagnetic means, a ratchet wheel, an opening pawl movable in response to operation of said relay for rotating said ratchet wheel during preselected closely succeeding opening operations of said relay, a timing device, and resilient means interconnecting said

ratchet wheel and said timing device, said resilient means allowing full opening movement of said relay without causing appreciable operation of said timing device when the fault current is in excess of a predetermined amount, said resilient means being effective to cause operation of said timing device and delayed opening operation of said relay for a substantial portion of the opening operation of said relay when the fault current is less than said predetermined value.

10. An operating mechanism for an electric circuit reclosing device having relatively movable contacts comprising electromagnetic means for imparting opening movement to said contacts, relay means responsive to fault currents for initiating operation of said electromagnetic means, means for imparting closing movement to said contacts, a ratchet wheel, an opening pawl movable in response to operation of said relay for rotating said ratchet wheel during preselected closely succeeding opening operations of said relay, a closing pawl movable with a movable one of said contacts for rotating said ratchet wheel in response to closing movement of said contacts, a timing device, and resilient means interconnecting said ratchet wheel and said timing device, said resilient means allowing opening movement of said relay without causing appreciable operation of said timing device when the fault current is in excess of a predetermined amount, said resilient means being effective to cause operation of said timing device and delayed opening operation of said relay for a substantial portion of the opening operation of said relay when the fault current is less than said predetermined value.
